Primary Examiner — Prabhakar Deshmukh(74) *Attorney, Agent, or Firm* — Knobbe, Martens, Olson & Bear, LLP(57) **CLAIM**

The ornamental design for a media player, as shown and described.

DESCRIPTION

FIG. 1 is a top, front and side perspective view of an embodiment of a media player embodying the new design; FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

Broken lines are used to illustrate features of the media player which form no part of the claimed design. The hatching of the embodiment illustrates a contrasting appearance.
